DESIGN FOR A COMBINATION CORKSCREW AND BOTTLE OPENER

Paul Wyler, Forest Hills, N. Y.

Application June 4, 1946, Serial No. 130,376

Term of patent 3½ years

(Cl. D44—29)

To the Commissioner of Patents:

Be it known that I, Paul Wyler, a citizen of Switzerland, residing at Forest Hills, in the county of Queens and State of New York, have invented a new, original, and ornamental Design for a Combination Corkscrew and Bottle Opener, of which the following is a specification: reference being had to the accompanying drawing, forming part thereof.

Fig. 1 is a front elevational view of a combination corkscrew and bottle opener, showing my new design.

Fig. 2 is a side view of Fig. 1.

Fig. 3 is a bottom view of Fig. 1.

Fig. 4 is a front elevational view of the corkscrew section of the article removed from the body of the article.

Fig. 5 is a fragmentary view of the bottom portion of Fig. 1, but illustrated with the bottom cap removed.

Fig. 6 is a side view of Fig. 5.

Fig. 7 is a side view of the bottom cap which was removed from Fig. 5.

I claim:

The ornamental design for a combination corkscrew and bottle opener, as shown.

PAUL WYLER.
